O. A. CLARK.
FOLDER FOR BLADES.
APPLICATION FILED AUG. 12, 1909.

959,995.

Patented May 31, 1910.

UNITED STATES PATENT OFFICE.

OSROE A. CLARK, OF NEWARK, NEW JERSEY.

FOLDER FOR BLADES.

959,995.

Specification of Letters Patent. Patented May 31, 1910.

Application filed August 12, 1909. Serial No. 512,498.

To all whom it may concern:

Be it known that I, OSROE A. CLARK, a citizen of the United States, residing at Newark, in the county of Essex and State of New Jersey, have invented certain new and useful Improvements in Folders for Blades; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

15 This invention relates to a folder or case for blades, and particularly for razor blades, which are provided with cutting edges and are of the thin or "wafer" kind. The blade is adapted to be securely held and at the same time be easily removed from the folder. The folder is also designed to prevent unnecessary contact of the edge of the blade with any foreign element or with the folder itself.

20 25 The invention is illustrated in the accompanying drawings, in which—

Figure 1 is a perspective view of the holder open, and with a blade in place. Fig. 2 is an edge view of the same folded. Fig. 3 is a top view of Fig. 2, and Fig. 4 is a section with the blade removed. Fig. 5 is a section, enlarged, on line 4—4 in Fig. 3, and Fig. 6 is a view of a modified form of construction.

35 The folder is constructed to hold blades with perforations therein, and consists of a sheet or plate 10 of any suitable material, such as paper or card-board, or a light metal might be used. The sheet 10 is provided with a raised or embossed portion 11 which is of approximately the same shape or is adapted to fit a perforated portion or portions 13 of a blade 14, which blade has cutting edges 15, although only one edge is 40 sharpened in some makes. The plate or sheet 10 is made wider than the blade so that its side edges extend beyond the blade, and the cutting edge of the blade is thus insured against contact with articles to dull it. 45 The sheet itself is also thus prevented from contacting with the blade. The present mode of wrapping these blades is to fold them individually in paper, which is wrapped over the ends and sides and then 50 secured either by a seal or similar fastening. This paper in contact with the cutting edges

is handled in the factory, the store, and by the user when unpacking or examining, and the edge of the blade is affected by this paper in contact with it, sufficiently to make 60 it dull. The sheet 10 is preferably flexible to a limited extent, although rigid material can be employed.

A cover is provided for fitting over the sheet 10 and its blade 14, and the cover can 65 be made integral with the sheet and folded over as shown at 16 in Figs. 1 to 5, or it can be made separate and placed thereon as in Fig. 6, where the cover is identified by the numeral 17. In the case of the folded cover 70 a seal 18 can be employed to fasten the cover and sheet together. In the device shown in Fig. 6 similar seals can be used or gummed surfaces 19 can be placed on the ends of either or both the sheet and the cover. 75

The raised or embossed portion of the sheet can be made in one piece as in Figs. 1 and 2, or made in a number of small lumps or bosses 20 to fit a number of perforations in the blade; and also to fit a blade with a 80 single slot.

The folder is cheap and simple, and securely holds a blade against loss or damage when handled with reasonable care.

The blade with its folder open can be laid 85 on the guard of a safety razor so that the raised portion is in register with the holding means on a razor, or the razor can be laid on the folder and the folder and the razor turned upside down to transfer the blade 90 from the holder to the razor frame without touching the blade with the hands. This is possible because there is no manipulation necessary to release the blade, except to remove the cover. 95

Having thus described my invention what I claim is:—

1. A holder for blades comprising a sheet of imperforate material with an embossed portion thereon adapted to enter the perforation in a perforated razor blade, and a cover to engage the embossed portion to prevent the blade being disengaged from the embossed portion. 100

2. A holder for blades comprising a sheet of material folded at the center to form one end into a cover, the sheet of material being embossed with a portion to fit the perforation in a perforated razor blade and project through the same to be engaged by the cover. 110

3. A holder for blades comprising a sheet of material with an embossed portion with

out perforation to enter the perforation of a
perforated razor blade, the embossed portion
permitting the blade's vertical removal there-
from without moving the blade transversely
5 or longitudinally, a cover adapted to cover
the blade and the sheet and engage the em-
bossed portion to lock the blade thereon.

In testimony, that I claim the foregoing, I
have hereunto set my hand this 11th day of
August 1909.

OSROE A. CLARK.
